(57) **CLAIM**

The ornamental design for a tumbler handle, as shown and described.

DESCRIPTION

FIG. 1 is a front perspective view of a tumbler handle showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is an enlarged view of a portion indicated with "9" in FIG. 2; and,

FIG. 10 is a perspective view of the tumbler handle shown in an environment of use.

The evenly dashed broken lines shown in FIG. 10 represent environment and form no part of the claimed design. All other evenly dashed broken lines represent portions of the tumbler handle that form no part of the claimed design. The dot-dash lines illustrate the border of the enlarged detailed views and form no part of the claimed design.
